Primary Examiner — Sandra S Snapp*Assistant Examiner* — Katherine Glennon(74) *Attorney, Agent, or Firm* — Dunlap Bennett & Ludwig PLLC(57) **CLAIM**

The ornamental design for a dive watch bezel, as shown and described.

DESCRIPTION

FIG. 1 is a perspective view of a dive watch bezel;

FIG. 2 is a front elevation view thereof; and,

FIG. 3 is a side elevation view thereof.

The broken lines shown in the drawings depict portions of a watch that form no part of the claimed invention.

1 Claim, 3 Drawing Sheets(56)
